UNITED STATES PATENT OFFICE.

HUGH EMILE FENCHELLE, OF GENOA, ITALY, ASSIGNOR TO WILLIAM L. KANN,
TRUSTEE, OF PITTSBURGH, PENNSYLVANIA.

FUEL-PUMP FOR INTERNAL-COMBUSTION ENGINES.

1,287,660.

Specification of Letters Patent.

Patented Dec. 17, 1918.

Application filed December 6, 1917. Serial No. 205,887.

To all whom it may concern:

Be it known that I, HUGH EMILE FENCHELLE, a British subject, residing at Via XX Settembre 34/4, Genoa, in the Kingdom 5 of Italy, have invented certain new and useful Improvements in Fuel-Pumps for Internal-Combustion Engines, of which the following is a specification.

This invention relates to fuel pumps for 10 internal combustion engines of the type employing ignition on Diesel lines, especially engines in which liquid fuel is injected mechanically as a spray without the use of spraying air, the invention more particularly relating to the suction valve of the 15 pumps and to improved means of controlling the said valve so as to vary the delivery of fuel by the pump.

According to this invention the amount 20 of fuel delivered is measured by the extent of movement of a reciprocating suction valve during the suction and compression strokes, which movement may be regulated by an adjustable stop. In the construction 25 preferred the suction valve is made in the form of a hollow piston with an internal non return valve and fuel passages leading from the supply channel, the reciprocating valve being drawn into the pump chamber 30 at the beginning of the suction stroke until the aforesaid stop prevents further movement, whereupon the continued outward movement of the pump plunger draws fuel through the valve into the pump chamber. 35 During the early part of the compression stroke of the pump the valve is driven back to its original position, when the remainder of the stroke is used to deliver the fuel under pressure through the delivery valve 40 to the spraying device. The amount of fuel delivered will of course vary inversely to the amount of idle movement of the pump plunger permitted by the backward movement of the suction piston valve.

45 In order that the said invention may be clearly understood and readily carried into effect the same will be more fully described with reference to the accompanying drawings, in which:—

50 Figure 1 shows in vertical section a pump constructed in accordance with the present invention, and

Fig. 2 is a detail view showing the valve stop device.

55 A is the pump body, B the plunger and C

an eccentric by which the pump is driven. D is the suction valve and E the delivery valve of the pump.

F is a regulating shaft by means of which the movement of the suction valve D is determined through the aid of the stop rod f.

The suction valve D, which is inclosed in the valve casing d perforated at d' and communicating with the fuel inlet channel a in the pump body A, contains a secondary 65 valve d² in the form of a ball normally lying against a seating in the hollow end d³ of the valve stem d⁴. At the outer end of this stem is a head or collar d⁵ comprising a small plate or disk adapted to meet the 70 end plate or stop f' on the stop rod f. The other end of this rod meets the flat face f² of the regulating shaft F, part of which shaft is cut away to leave a semi-cylindrical portion. The regulating shaft is operated 75 through the lever arm f³ and rod f⁴ connected to the engine governor or to any type of regulating apparatus.

The operation of the pump is as follows:—

The stroke of the pump plunger B is constant but on beginning the suction stroke, so as to draw fuel into the pump chamber a', the suction valve, which is free to slide in the valve casing d under the action of the spring d⁶ tending to force the end of the 85 valve into the chamber a', is allowed to move into this chamber as the pump plunger rises, until the disk or collar d⁵ on the valve stem d⁴ meets the stops plate f'. The further movement of the piston valve D being then 90 stopped, the pump plunger begins to draw fuel through the passages a, d' and the hollow piston valve D into the pump chamber a' which is kept full of fuel. On beginning the delivery stroke of the pump the pressure 95 on the fuel first drives back the piston valve D, the small internal ball valve d² closing immediately the delivery stroke begins so as to prevent the fuel in the chamber a' flowing back through the interior of the valve D. 100 During a portion of the delivery stroke, the extent of which depends upon the previous inward movement of the valve D, the fuel is not subjected to appreciable pressure and only when the valve D closes against its 105 seating can the delivery pressure be exerted on the fuel. For the rest of the delivery stroke the fuel is driven, under the high pressure desired for spraying purposes, through the delivery valve E and the outlet 110

e to a fuel spraying device fitted in the engine cylinder.

The extent of movement allowed to the piston valve D depends upon the position 5 of the stop plate f' and this is under the control of the regulating shaft F. The angular adjustment of the regulating member or shaft F determines the point at which the stop plate f' arrests the inward movement 10 of the valve D. The earlier in the suction stroke of the pump the valve movement is arrested, the greater is the quantity of fuel drawn into the pump chamber and delivered to the engine, the inward adjustment 15 of the stop f' giving increased play or idle movement to the valve D with consequent decreases of the fresh fuel drawn through the valve into the pump chamber. The valve D may when desired be entirely 20 freed from stop control by, for example, forming the stop plate f' with a notch f'' (Fig. 2) at one side so that when the stop rod f is turned to the freeing position the disk d⁵ on the valve stem d⁴ can pass the 25 stop plate f' and, if the pump plunger B continues to be driven, it simply moves the suction valve D in and out without delivering any fuel. The pump delivery can therefore be cut off by a simple rotation of the 30 valve stop f'.

The suction valve itself may be used as a small hand operated piston pump to fill the tubes and passages with oil and to expel the air before starting the engine and, as the 35 valve can be completely controlled from outside during the working of the engine, it may be turned to dislodge any impurities which may accumulate between the valve and its seat. A small conical seating in the 40 casing d is preferably provided against which a conical lip on the end of the valve D closes when the valve is driven back.

What I claim and desire to secure by Letters Patent of the United States is:—

45 1. In a measuring pump, a reciprocating pump plunger, a suction valve controlling the inlet to the pump chamber and actuated by the suction and compression actions of said plunger, and means whereby said valve 50 may follow the suction stroke of the plunger idly for a predetermined portion of the suction stroke without admitting fluid therethrough to the pump chamber.

55 2. In a measuring pump, a reciprocating plunger, a reciprocating suction valve actuated by said plunger of piston form adapted to follow up the movement of the plunger through a predetermined portion of its stroke and means for regulating the range 60 of movement of the piston valve.

65 3. In a measuring pump, a pump chamber, a plunger therein, a reciprocating suction valve controlling the inlet to said chamber and actuated by the action of the said plunger, said valve having a limited range

of movement in the pump chamber, during which movement liquid neither enters nor leaves the said chamber, and means for regulating the range of such movement.

4. In a measuring pump, a reciprocating plunger, a reciprocating suction valve of piston form free to follow the movement of liquid at the beginning of the suction and delivery strokes of the plunger without passage of the liquid past the valve and an adjustable stop limiting the range of movement 75 of the valve.

5. In a measuring pump, a pump chamber, a reciprocating plunger, a reciprocating hollow piston suction valve through which the fuel passes, the said valve being adapted 80 to be drawn into the pump chamber without passage of the liquid during a portion of the suction stroke of the plunger, and an adjustable stop preventing further inward movement of the valve.

6. In a measuring pump, a hollow reciprocating piston suction valve, a secondary non-return valve situated in the said piston valve and means for regulating the range of movement 90 of the said piston valve.

7. In a measuring pump, a reciprocating piston, a reciprocating suction valve of piston form adapted to follow the movement of the plunger through a predetermined portion of its stroke, an abutment member on the outer end of the said valve, an adjustable sliding stop adapted to meet the valve abutment and a regulating shaft the angular adjustment of which determines the 95 position of the said stop.

8. In a measuring pump, a reciprocating plunger, a reciprocating suction valve adapted to measure the liquid delivered by following up the movement of the plunger 105 so as to render a portion of the stroke idle, means for regulating the range of movement of the said valve, and means for releasing the said valve from control so that it can follow up the plunger during the entire 110 stroke.

9. In a measuring pump, a reciprocating plunger, a reciprocating suction valve of piston form free to follow the movement of liquid at the beginning of the suction and 115 delivery strokes of the plunger without passage of the liquid past the valve, an adjustable stop limiting the range of movement of the valve, and means for freeing the valve from the said stop to allow the valve to follow up the plunger movement through the entire stroke.

10. In a measuring pump, a reciprocating plunger, a reciprocating suction valve of piston form free to follow the movement of liquid at the beginning of the suction and delivery strokes of the plunger without passage of the liquid past the valve, an abutment member on the valve, and an adjustable stop plate adapted normally to meet 125

130

the said abutment at a predetermined point in the pump stroke and on turning through an angle to clear the said abutment so as to free the valve from control.

- 5 11. In a measuring pump, a reciprocating pump plunger, a reciprocating suction valve controlling the admission of fluid to the pump chamber and actuated by the plunger, said valve being constructed and arranged to follow the movement of the pump plunger 20 through a predetermined portion of its stroke, a stop member for limiting such movement, and means for adjusting the position of the stop, said valve having an externally projecting handle portion whereby 25 the valve may be actuated to act as the piston of a hand pump to deliver fluid into the pump chamber.
- 10 12. In a measuring pump, a reciprocating

pump plunger, a reciprocating suction valve controlling the admission of fluid to the pump chamber and actuated by the plunger, said valve being constructed and arranged

to follow the movement of the pump plunger through a predetermined portion of its stroke, a stop member for limiting such movement, and means for adjusting the position of the stop, said valve having an externally projecting handle portion whereby the valve may be actuated to act as the piston of a hand pump to deliver fluid into the pump chamber.

HUGH EMILE FENCHELLE.
